(57) **CLAIM**

The ornamental design for a curling iron head, as shown and described.

DESCRIPTION

FIG. 1 is a front, right and top perspective view of a curling iron head, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and top perspective view of the curling iron head in use state.

The broken lines shown in the drawings illustrate portions of the curling iron head that form no part of the claimed design.

1 Claim, 9 Drawing Sheets
